UNITED STATES PATENT OFFICE.

WALTER J. JOHNSON AND ARTHUR L. JOHNSON, OF CHICAGO, ILLINOIS.

CHAIR-SEAT.

1,188,453.

Specification of Letters Patent. Patented June 27, 1916

Application filed March 17, 1915. Serial No. 14,888.

To all whom it may concern:

Be it known that we, WALTER J. JOHNSON and ARTHUR L. JOHNSON, citizens of the United States, residing at Chicago, in the county of Cook and State of Illinois, have invented a certain new and useful Improvement in Chair-Seats, of which the following is a specification.

Our invention relates to chair seats, more particularly of the type wherein a portion of the seat is removable.

One of the objects of the invention is to provide a construction in which the front rail of the removable or "slip" seat constitutes the foremost rail of the chair.

Another object is to provide a seat which may be removed from the seat frame without raising the seat, but merely slipping it in a forward direction.

Another object is to provide in a seat of this character a front extending entirely or approximately across the entire width of the chair.

A fourth object is to provide a slip seat lending itself particularly to a so-called "saddle" shape.

Fifth, it is our object to produce a configuration rendering it practical to employ leather covered cane seating in a saddle shaped seat.

We accomplish our objects by the construction shown in the accompanying drawings, in which—

Figure 1 is a top view of the slip seat and its support, a portion of the leather being removed and a portion of the padding or lining being also removed to better reveal the construction of the parts. Fig. 2 is a top view of the support with the seat removed.

Fig. 3 is a vertical section on the line 3, 3 Fig. 1, and Fig. 4 is a vertical section on the line 4, 4 Fig. 1.

Similar numerals refer to similar parts throughout the several views.

Referring to the drawings in which a preferred embodiment of the invention is shown, the stationary support for the seat consists of a front rail 1, side rails 2, 2, and a back rail 3. Over this support lie two side rails 4, 4 and a back rail 5, which are set back somewhat from the inner margins of the parts 2 and 3 to afford a supporting ledge or shoulder for the seat. Said rails 4 and 5 rise preferably to the height of the

slip seat and form stops or abutments therefor. The major portion of the front rail 1 remains uncovered. In consequence it may be said that the rails 4, 4, 5 are open at the front. Theoretically these parts might be carved from a single piece, but as a practical matter of manufacture the different elements referred to should be made of separate pieces of wood, glued or otherwise rigidly secured together. The side rails 4 are curved outwardly at their forward ends and by preference do not reach quite to the forward edge of the front rail.

The preferred arrangement of the parts is clearly shown in Fig. 2. The parts mentioned form a permanent and stationary part of the chair, and as the legs, back, and arms of the chair may assume many different forms, and as such parts are well known, it is thought unnecessary to illustrate them.

The slip seat comprises a frame having a front rail 7, two side rails 8, 8 and a back rail 9. These parts are preferably made of four pieces of wood suitably joined together. They conform in general to the outline of the stationary support, the front rail 7 resting upon the front rail 1 and the side and back rails resting upon the exposed marginal edges of the side rails 2 and back rail 3 respectively. The forward edge of the front rail 7 comes flush or somewhat in front of the forward edge of the front rail 1 and at the ends swings out so as to come in front of the forward ends of the side rails 4. Thus the slip seat presents a continuous front, entirely across the width of the chair.

The front rail 7 when viewed in cross-section, as on the line 3, 3, Fig. 1 is rounded somewhat as in a saddle, there being a center ridge 7^a flanked by two depressions 7^b as clearly shown in Fig. 3. A tongue 7^c projects inwardly from the center of the rail 7 and this renders it possible to extend the center ridge and carry the same on a slow taper down to or below the level of the innermost edges of the rails 8, 9. Said side rails and the back rail 9 are dished as shown in Figs. 3 and 4, the outer edges being flush with the top of the rails 4, 5 and the inner edges inclining downward as shown.

The area bounded by the rails 7, 8 and 9 is covered by cane-seating 11, fastened in any suitable manner to the rails of the slip

seat. Overlying this cane-seating is a leather cover 12, and by preference a lining 13 of felt or other suitable material is interposed between the cane-seating and the cover. The cover extends around over the front edge of the front rail 7 and is secured along the under edge, covering the entire top surface and sides of the slip seat, and thereby imparting a finished appearance thereto. When the slip seat is in place the fastening of the cover to the frame work is not apparent.

We call particular attention, in addition to the general features of construction, to the presence of the tongue 7^c. This tongue renders it possible to employ cane seating upon a "saddle shaped" chair seat. The front end of the center ridge 7^a is comparatively high, much higher than the elevation of the central portion of the seating. By thus providing the tongue it is possible to avoid a sharp drop at the inner edge of the front rail which would have a tendency to very soon cut the cane. With our construction it is possible to taper off the ridge to a point flush with or below the plane of the caning. By protecting the cane, the leather covering is also protected, for the cover co-operates with the caning in supporting the weight of the person using the chair.

As a result of the construction shown, the leather cover is brought to the fore-front of the seat under the knees of the user and this covered front extends throughout the entire width of the chair. This avoids any ridges or unevenness, such as is frequently found in chairs in which the stationary front rail comes in front of the removable seat. Furthermore, as the seat is "saddle shaped" it is comfortable, especially in view of the fact that instead of being solid wood as saddle seats usually are, it is made of leather covered cane, with a cushion lining. When it is desired to remove the seat, this may be done by merely slipping the same forward or merely lifting up on the front edge of the front rail which is at all times convenient to the grasp of the user. In the ordinary construction it is frequently difficult to remove the seat and usually it is necessary to reach under and push up from beneath, a draw back that is avoided in a chair of our construction.

Having thus described our invention,

what we claim as new and desire to secure 55 by Letters Patent, is:—

1. In a chair, the combination of a stationary support having marginal strips rising therefrom at the sides and back, said strips at the sides terminating short of the 60 front edge of said support; and a slip seat fitting within the marginal strips on the stationary support and extending to a point in front of them, and extending, across the front, approximately to the outer edges of 65 the side marginal strips.

2. A chair having a stationary support having a front rail, side rails and a back rail rising above the level of said support, the ends of the side rails being rounded outward at the front ends; and a slip seat resting upon said support and abutting said rails to be held laterally thereby, the top of the seat being substantially flush with the top of the side and back rails of the 75 support, and said seat having a front rail having laterally extending wings at the ends rounding outward around the front ends of the side rails of the support and terminating substantially at the outside 80 edges of said side rails, the spread of the wings being substantially equal to the greatest width of said support.

3. In a chair, a slip seat consisting of a frame having a front rail, side rails and a 85 back rail, and a flexible covering stretched over said frame, the front rail being saddle shaped and having a tongue projecting inwardly toward the center of the seat, the front rail having a center ridge which tapers 90 down onto said tongue.

4. In a chair, a slip seat consisting of a frame having a front rail, side rails and a back rail and a flexible covering stretched over said frame, the front rail having a 95 center ridge, and a tongue projecting inwardly toward the center of the frame at least half way to said center, said tongue carrying the ridge down as far as the level of the adjacent inner edges of the side rails. 100

In witness whereof we have hereunto subscribed our names in the presence of two witnesses.
